Ice Machinery Corporation, York, Pa., a corpo-
ration of Delaware

Application June 29, 1935, Serial No. 29,133

10 Claims. (Cl. 230—206)

This invention relates to lubricating means for refrigeration systems of the type in which a plurality of compressors operate in parallel relation and supply compressed gas to a refrigerating circuit.

In systems of this character it is usual to lubricate the compressors by the "splash" system in which the crank cases of the compressors act as sumps for the lubricating oil and are in communication with the low pressure side of the circuit. Where a plurality of compressors are operated in parallel, it is usual to cut them in or out, in accordance with the load on the refrigerating circuit, the control being either manual or automatic. Consequently, conditions arise where certain of the compressors are idle when others are operating.

Frequently the lubricating oil flows in suspension in the gaseous or liquid refrigerant, and this is particularly true when the refrigerant is one of the recently developed types, such as that known by the trade name of "Freon". When the refrigerant comes back to the low side of the compressors from the evaporator, the oil carried by the refrigerant may flow into the crank case of one particular compressor to overfill it, while the level in other machines is reduced to a dangerously low level.

Various experiments have shown that some means must be provided for equalizing the oil level automatically in the crank cases of two or more compressors connected in parallel to common suction and discharge lines, at such times as the crank case pressures of two compressors become equal. It has also been found to be equally important, as hereinafter explained, to prevent oil flow from one crank case to another at all times when the crank case pressures are unequal.

Equalization of the oil level between the crank cases of the various compressors can be obtained by providing equalizing connections between points of proper oil level in the various crank cases. A constantly open connection is, however, not satisfactory, because the crank case pressures of different compressors may vary. When, for example, one or more of the machines is idle, crank case pressure tends to build up in the machine or machines which are active and this results in the oil from the crank case of an operating machine being displaced and transferred to the crank case of an idle machine. Obviously, such a condition must be avoided since it may result in a compressor running dry.

Consequently, it is proposed, according to this invention, to provide equalizing connections be-

tween the crank cases of the compressors, and to include in each connection a check valve having a moderate opening tendency. This valve will operate to prevent oil from being forced from the crank case of one machine to that of another by pressure differential developed between the crank cases of such machines, but will not prevent the equalizing gravity flow of oil when adjacent machines are inactive or when the pressures are equalized.

The invention will be more fully understood when the following specification is read in conjunction with the drawings in which:

Figure 1 is a diagrammatical view of one form of refrigeration system embodying this invention; 15

Figure 2 is a detail sectional view of a double check valve which may be used in carrying out this invention;

Figure 3 is a view similar to Figure 1, but showing a modified arrangement of oil equalizing connections, also embodying this invention; 20

Figure 4 is a sectional view of a check valve suitable for use in the system of Figure 3.

For purposes of illustration the invention has been shown in Figure 1, as embodied in a simple refrigeration system of the direct expansion type, although it is to be understood that it is of general application and may be used in connection with a system of the flooded type or in any system in which a plurality of compressors are connected in parallel with the refrigerating circuit and are capable of independent or conjoint operation.

Referring to Figure 1 the reference characters C1, C2 and C3 designate three compressors connected in parallel relation on their high sides to a common pressure line 8 leading to a condenser 9. The system includes a line 11 running from the condenser 9 to a liquid receiver 12; a line 13 and an expansion valve 14 connecting the out flow of receiver 12 to the inlet of evaporator 15, and a return or suction line 16 connecting the evaporator with the low sides of the compressors C1, C2 and C3 in parallel.

The three compressors shown will normally, although not necessarily, be arranged to be cut in serially according to the load on the refrigerating circuit, and to be cut out serially in reverse order. For example, under light load conditions the compressor C1 may operate alone. When the load increases, compressor C2 may be cut in so that the two machines C1 and C2 operate in parallel to feed the circuit. Upon further increase in load the machine C3 may be cut in.

On falling loads machine C3 will cut out first, then machine C2 and finally machine C1.

Each of the compressors C1, C2 and C3 has a crank case 17 which acts as a sump for lubricating oil. Connected between the crank cases 17 of the compressors C1 and C2, at or below the normal oil level therein, is an equalizing connection or line 18 containing a two-way check valve 20. A similar equalizing connection 19 containing a two-way check valve 21 is placed between the compressors C2 and C3. If only two machines are used, a single equalizing connection will be present, but if additional compressors are used additional equalizing connections will be made so that the crank cases of all the machines are connected by a line similar to line 18 or 19.

Referring to Figure 2, the check valve comprises a tubular body 20 threaded at both ends for connection to the equalizing line. The interior of the body comprises a central cylindrical chamber 22 partially closed at each end by a sleeve 23 threaded into the body 20 and having slots 24 for the reception of a wrench or screw driver. The inner end of each of the sleeves 23 has a countersunk seat for sealing cooperation with a ball check 26 which, under conditions of equal pressure at both ends of the chamber 22, gravitates to substantially the mid point of this chamber, as shown in Figure 2. When a pressure differential exists between the ends of the chamber 22, the ball 26 is forced into contact with the seat 25 of one or the other of the sleeves 23 thereby closing the equalizing connection against flow of lubricant. In moving to sealing engagement with either seat the ball is raised slightly against the attraction of gravity. Consequently, the ball check may operate in either direction to prevent flow of lubricant between the crank cases of machines having unequal pressures. When, however, the crank pressures of two connected machines become substantially equal, the ball 26 will fall away from both of the seats 25. The oil flow will then be insufficient to lift the ball to sealing position, leaving substantially unrestricted connection between the two ends of the chamber 22 and permitting equalizing flow of oil from one crank case to the other. It is unnecessary to provide an equalizing connection between the crank cases of compressors C1 and C3, because of the order in which the compressors are put into and out of action. Hence no such connection is shown. Obviously the use of this additional connection is within the scope of the invention.

The operation of the two-way check in the complete system shown may be stated briefly as follows:

When the compressor C1 alone is operating, its crank case pressure will predominate over that of the two idle machines. Consequently, the ball 26 will move against the left hand seat 25 of valve 20 and prevent flow of oil from the crank case of machine C1 to that of machine C2. If machine C2 then starts up, pressure between the crank cases of machines C1 and C2 will be substantially equalized and the check 20 will open, while the check 21 between machines C2 and C3 will close. If machine C3 is likewise operating, both checks 20 and 21 will open, and the pressure will be substantially equalized among the three crank cases. When machine C3 shuts down, the check 21 between that machine and C2 will close to prevent oil from being discharged from the crank case of C2 to that of C3, and a similar operation of check 20 will occur when

machine C2 shuts down. When all of the machines shut down both checks will open and the oil level will equalize among the three machines.

While the invention has been described in connection with a system including a plurality of compressors connected in parallel and adapted for serial operation, the preferred arrangement is such that the compressors may operate in any order, and consequently flow of oil from one compressor to another is prevented whenever a pressure differential exists between any two machines. Figure 3 of the drawings illustrates a system of this character having the same evaporator, receiver and condenser arrangements as those shown in Figure 1.

Referring to Figure 3, the reference characters 37, 38 and 39 designate three compressors having pressure connections 5, 6 and 7, respectively to the pressure side 8 of the refrigerating circuit. Similarly the suction connections 27, 28 and 29 of these machines are made to the suction side 16 of the refrigerating circuit.

In this arrangement, the compressors 37, 38 and 39 may operate in any order, as for example, when the system is subject to manual control. Under such circumstances the operator would employ a number of machines commensurate with the refrigerating load, and would cut machines in or out, in accordance with variations in this load. A failure of one of the machines might result in a complete change in the order of operation, consequently, it is desirable to have the oil equalization independent of the order in which the compressors are put into or taken out of operation.

As shown in the drawings, the oil equalizing connection comprises a main line 31 between the crank cases 17 of the machines 37 and 39, and a branch line 33 interposed between the line 31 and the crank case 17 of compressor 38. The oil equalizing connection has interposed between it, and each of the crank cases 17 of the three compressors, a check valve 32 preferably constructed and arranged as shown in Fig. 4. All of these valves are similar, hence a description of one of them will suffice. This check valve is generally similar in form to that shown in Figure 2, except that in this case the arrangement is such that the ball need seat in one direction only. The valve comprises a valve body 32 threaded at 41 into the wall of a crank case 17 and threaded at its opposite ends into a nipple 42 adapted to form a pressure tight seal with the line 31. The body of the valve 32 is preferably formed on the outside for the reception of a wrench. It contains a chamber 34 similar to the chamber 22 of double check valve 20 previously described. The end of chamber 32, adjacent the crank case 17, is closed by a threaded sleeve 35 having wrench slots 24, and preferably formed at its end, adjacent the ball check 36, with a flat face, since this ball check need have a sealing connection at one end only of chamber 34. The outer end of chamber 34 contains a second threaded sleeve 23 having slots 24 and being otherwise similar to the sleeves 23 described in connection with the double check valve previously described.

Consequently, when pressure is substantially equalized between the inside of one of the crank cases 17 and the line 31, the ball 36 gravitates to the position shown in Fig. 4. Whenever a pressure differential is formed, however, so that the pressure within the crank case 17 predominates over that in line 31, the ball 36 will be lifted slightly and into contact with the seat 25 on

sleeve 23, thus sealing the crank case 17 against escape of oil therefrom. As soon as pressure between the crank case and the line 31 is equalized, the ball 36 will gravitate again to the position 5 shown in Fig. 4 so as to permit free equalizing flow of oil from one crank case to another through the line 31 or the line 31 and branch line 33, as the case may be. It will be obvious that because of this arrangement of a ball check associated with each of the compressors 37, 38 and 10 39, there can be no flow of oil from one crank case to another, when a pressure differential exists between any two machines. Rise in pressure within any one of the three crank cases 15 will cause the associated check valve 32 to close, thus cutting off the flow of oil through the equalizing connection.

It will be understood that the system shown in Figure 3 produces results similar to those of the 20 apparatus of Figure 1, except that it is entirely independent of the order in which the compressors start or stop, and a one-way check valve is sufficient, since a check valve is associated with each of the compressors. Consequently, the embodiment of the invention shown in Figure 3 offers a flexibility of operation which is not possible with the system shown in Figure 1.

The invention described is of particular utility in systems where there is a marked tendency for 30 the lubricating oil to flow in suspension in the liquid or gaseous refrigerant, and it forms a simple way of insuring that the oil level will always remain substantially equalized among all of the compressors which are in parallel. Although the invention has been described in connection with a direct expansion system having three compressors, it is not so limited, and it will be obvious that it may be applied to any system having any number of compressors operating in parallel. Consequently, no limitations other than those directly expressed in the claims 40 are implied.

What is claimed is:

1. In a lubrication system, a circuit for a volatile liquid medium; a plurality of compressors connected in parallel in said circuit and arranged to operate, one or more at a time, in accordance with the load on said circuit, each of said compressors having an oil sump subject to the suction pressure of the circuit; a lubricating conduit connecting the sums of said compressors; and means in said conduit for preventing flow of lubricant from one sump to another when a material pressure differential exists between them, but permitting equalizing flow between said sums when their pressures are substantially equal.

2. In a lubrication system, a circuit for a volatile liquid medium; at least two compressors having individual suction connections and individual 60 discharge connections with said circuit, and each having an oil reservoir subject to the suction pressure of the circuit; a lubricant level equalizing conduit connecting the reservoir of each compressor to the reservoir of the adjacent compressor; and means in each of said conduits for permitting lubricant equalizing flow between adjacent inactive compressors but preventing flow between an active and an inactive compressor.

3. In a lubrication system, a circuit for a volatile liquid medium; at least two compressors connected in said circuit in parallel relation to one another and adapted for simultaneous or individual operation; a lubricant sump in each of said compressors subject to the suction pressure of 70 the circuit; a lubricant conduit connecting the

sump of each compressor to that of another; and means in each conduit for preventing flow of lubricant from one sump to another when a pressure differential exists between them, but permitting free equalizing flow between the sums of the compressors when their pressures are equal.

4. In a lubrication system, a circuit for a volatile liquid medium; a plurality of compressors having individual suction connections and individual discharge connections with said circuit; a lubricant sump associated with each of said compressors and subject to the suction pressure of the circuit; a lubricant level equalizing conduit between each sump and another; and a two-way check valve in said conduit, said valve being arranged to prevent lubricant flow from the sump of an active to that of an idle compressor and permitting equalizing flow between the sums of idle compressors.

5. The combination of a closed circuit for a volatile liquid medium; at least two compressors connected in parallel in said circuit and capable of independent and conjoint operation, said compressors being of the type in which lubrication is effected from a charge of oil carried in the crank case, and the crank case is subject to the suction pressure in the system; a normally open oil level equalizing connection between the crank cases of such compressors; and means effective when a compressor is idle to close the equalizing connection between its crank case and the crank case of an active compressor.

6. The combination of a closed circuit for a volatile liquid medium; at least two compressors connected in parallel in said circuit and capable of independent and conjoint operation, said compressors being of the type in which lubrication is effected from a charge of oil carried in the crank case, and the crank case is subject to the suction pressure in the system; a normally open oil level equalizing connection between the crank cases of such compressors; and means responsive to pressure differential between the crank cases of the compressors, for at times closing said equalizing connection to prevent flow of oil from one crank case to another.

7. In a lubrication system, a circuit for a volatile liquid medium; a plurality of compressors connected in parallel relation to one another to supply high pressure gas to said circuit, and to receive low pressure gas from said circuit; an oil collecting reservoir in the low side of each of said compressors; an oil level equalizing conduit connecting all of said reservoirs together; and a two-way check valve interposed in said conduit between the reservoir of each compressor and that of an adjacent compressor, said valves being gravity operated to permit equalizing flow of oil from one compressor to another when the reservoir pressures are equal, but responsive to a pressure differential between adjacent compressors to prevent flow of oil from one compressor to another.

8. In a lubrication system, a circuit for a volatile liquid medium; a plurality of compressors having their crank cases formed to act as lubricant reservoirs subject to the suction pressure of the circuit and also subject to variable pressure depending upon whether they are active or idle; means for connecting said compressors to said circuit in parallel relation to one another; a lubricant level equalizing conduit connecting all of said reservoirs together; and a check valve interposed in said conduit between each compressor and another, said valve being biased by gravity

to open position when two adjacent compressors are idle, and closed by the pressure differential existing when one of two adjacent compressors is idle and the other is active.

5. 9. In a lubrication system, a circuit for a volatile liquid medium; a plurality of compressors connected in parallel with said circuit, and having oil reservoirs subject to the suction pressure of the circuit; means for permitting equalizing 10 flow of lubricant from the oil reservoir of one compressor to that of another when the pressures in these reservoirs are substantially equal; and means responsive to pressure differential between said reservoirs for preventing flow of lubricant 15 from one reservoir to another.

10. The combination of a circuit in which a volatile liquid medium is converted between the liquid and vapor phases by changes of pressure and temperature, such circuit including a plural-

ity of compressors connected in parallel therein, and capable of individual and conjoint operation, said compressors having oil sumps subject to the suction pressure, from which sumps the compressors are lubricated and the circuit being so arranged that lubricant if entrained with the volatile medium will be returned to at least one of said sumps; oil level equalizing connections between the sumps of respective compressors; and check valve means interposed in said equalizing connections, said check valve means having an opening bias sufficient to maintain them open against differences in hydrostatic pressure occasioned by differences of oil level, but insufficient to maintain them open against differentials of 10 suction pressure between different compressors, one of which is operating and the other of which is inactive.

ROBERT W. ZERCHER.
